Thoeming(57) **CLAIM**

The ornamental design for a combined bottle light and shade, as shown and described.

DESCRIPTION

FIG. 1 is an isometric top view of a combined bottle light and shade showing our new design;

FIG. 2 is an isometric bottom view thereof;

FIG. 3 is a top plan view thereof;

FIG. 4 is a bottom plan view thereof;

FIG. 5 is a front elevation view thereof, the rear, right side and left side views being identical thereto;

FIG. 6 is a first isometric top view of the combined bottle light and shade shown in an environment of use;

FIG. 7 is a second isometric top view of the combined bottle light and shade shown in an environment of use;

FIG. 8 is a third isometric top view of the combined bottle light and shade shown in an environment of use; and,

FIG. 9 is an isometric bottom view of the combined bottle light and shade shown in an environment of use.

The broken line portions shown in FIGS. 6 through 9 illustrate environmental subject matter only and form no part of the claimed design.
